UNITED STATES PATENT OFFICE.

AUGUSTUS L. HAHL, OF CHICAGO, ILLINOIS, ASSIGNOR TO HAHL AUTOMATIC CLOCK COMPANY, OF CHICAGO, ILLINOIS, A CORPORATION OF ILLINOIS.

PNEUMATIC CLOCK SYSTEM.

No. 910,373.

Specification of Letters Patent.

Patented Jan. 19, 1909.

Application filed September 11, 1905. Serial No. 277,810.

To all whom it may concern:

Be it known that I, AUGUSTUS L. HAHL, a citizen of the United States, residing at Chicago, county of Cook, State of Illinois, have invented a certain new and useful Improvement in Pneumatic Clock Systems, and declare the following to be a full, clear, and exact description of the same, such as will enable others skilled in the art to which it pertains to make and use the same, reference being had to the accompanying drawings, which form a part of this specification.

My invention relates in general to clocks, and more particularly to pneumatic clock systems.

In pneumatic clock systems, such for instance as that covered by U. S. Letters Patent No. 598,066, granted to me Jan. 25, 1898, a master clock controls the operation of a motor for supplying and exhausting impulses of air to and from systems of service tubes with which communicate at predetermined points air chambers actuated both by the supply and exhaust of air impulses to operate subordinate clocks in unison with the master clock. In my prior patent, the impulse mechanism comprises two bellows with each of which a system of subordinate clocks communicates by service tubes, the bellows being so connected by a lever that as one is distended by the motor the other is compressed. The work imposed upon the motor at the master clock in alternately compressing the bellows gradually increases from nothing to its maximum as each bellows is compressed. The power of the motor is therefore necessarily sufficiently great to exert the force requisite to complete the compression of the bellows, and is consequently greatly excessive at the commencement of its operation, which results in imparting to the motor a jerking and irregular motion.

The primary object of my invention is to provide a pneumatic clock system of the type covered by my said prior U. S. patent, in which a motor may be employed having approximately one-half the power necessary to exert the pressure required to complete the alternate compression of the bellows, thereby rendering it possible to reduce the size of the motor for a given number of clocks with a corresponding reduction in the cost of installing and operating the system, and also making the operation of the motor more uniform.

A further object of my invention is to provide in a clock system a direct detent requiring much less overbalancing than a warning detent, actuated at predetermined intervals by the time train of a master clock for releasing the motor to actuate the impulse mechanism and also for opening the valve from the service pipe containing pressure, which will impose a minimum load upon the time train and will relieve the same from all pressure from the motor train.

A still further object of my invention is to provide in a pneumatic clock system yieldingly seating valves, for controlling the atmospheric exhaust from the service tubes in which the pressure in the tubes assists in seating the valves.

A still further object of my invention is to provide an improved pneumatic clock system by means of which a maximum number of clocks may be efficiently operated at a minimum cost.

My invention will be more fully described hereinafter with reference to the accompanying drawings in which the same is illustrated as embodied in a convenient and practical form, and in which:

Figure 1. is a front elevational view: Fig. 2. a detail elevational view of the tripping mechanism prior to being tripped; Fig. 3. a view similar to Fig. 2 after the tripping has occurred; Fig. 4. a view similar to Fig. 3. with the parts in position after closing the valve of the service pipe; Fig. 5. a view similar to Figs. 3 and 4, showing the parts in the position they assume immediately before the motor is stopped; Fig. 6. a plan view of the tripping mechanism; Fig. 7 a sectional view on line 7—7, Fig. 5; Fig. 8. a sectional view through the valves taken on line 8—8, Fig. 6; Fig. 9. a detailed view of the impulse mechanism showing the auxiliary rolling weight at the point of being shifted to aid in the compression of the bellows F²; and Fig. 10. a view similar to Fig. 9 showing the auxiliary rolling weight at the point of being shifted to assist in compressing the bellows F.

The same reference characters are used to designate the same parts in the several figures of the drawings.

Reference characters A' and A² indicate power shafts suitably journaled in brackets w' and w² depending from supporting frame W. Mounted upon the power shafts A' and A² are drums a' and a² around each of which

- is secured a weight cord a . It will, of course, be understood that other motive power than weights may be employed if desired. Fixed to the power shafts are gear wheels B' and B^2 which mesh with an intermediate pinion b , fixed to a shaft B . A gear wheel C is also fixed to the shaft B and meshes with a pinion c fixed to a shaft C' , the latter being suitably journaled in the supporting frame as at W' .
- 5 A gear wheel c' is fixed upon the shaft C' and meshes with a pinion d' fixed upon a shaft D' . A crown gear wheel D is fixed upon the shaft D' and meshes with a pinion d^2 fixed upon a vertical staff D^2 , the latter being journaled at its lower end in a bracket v' and at its upper end in a bracket v^2 . Fixed upon the staff D^2 is a fly governor D^3 . A radial arm d^3 projects from the staff D^2 preferably at a point immediately above the pinion d^2 .
- 10 Projecting from the shaft D' is a crank arm d' to which is pivotally connected a link e , the upper end of the latter being pivotally connected to a bracket secured to a lever E . The lever E is fulcrumed intermediate of its ends upon the upper end of the frame W' . The opposite ends of the lever E are pivotally connected to rods f' and f^2 , respectively, by means of pins f, f , engaging holes in the lever. The lower ends of the rods are secured to bellows F' and F^2 , mounted upon the upper ends of pipes F^3 and F^4 with which they communicate. The pipes F^3 and F^4 are supported in vertical positions by blocks h' and h^2 which are adjustable laterally between the supporting frame W and a slotted guide plate H secured thereto. The lower ends of the pipes F^3 and F^4 communicate with service pipes H' and H^2 leading to air chambers located at predetermined points for actuating subordinate clocks.
- 15 Branch pipes K' and K^2 extend from the main pipes H' and H^2 and communicate therewith by means of T-couplings k' and k^2 , respectively. The ends of the branch pipes lead to valve casings K^3 and K^4 supported upon the frame W^2 . Each of the valve casings is provided with a cap k surrounding the upper end thereof and securing thereto a coupling at the end of the respective branch pipe. Located within the valve casings are valves L' and L^2 which coöperate with valve seats to control the exhaust ports k^3 and k^4 leading to the atmosphere. The valves L' and L^2 are provided with depending valve stems l' and l^2 , which extend through the valve casings and are guided at their lower ends in brackets l^3 and l^4 . Surrounding each valve stem is a spring l bearing at its lower end upon a pin l^5 and at its upper end
- 20 engaging a collar l^6 loosely surrounding the valve stem and limited in its upward movement by a pin l^6 . Fulcrumed upon a bracket w^2 extending from the supporting frame W^2 are valve actuating levers M' and M^2 the former of which is provided with a yoke m^3 en-
- 25 gaging the collar l^6 on the valve stem l' , while the latter of said levers is provided with a similar yoke for engaging the collar on the valve stem l^6 , as clearly shown in Fig. 8. The ends of the levers M' and M^2 are provided with counter-balancing weights m . The valve actuating levers extend inwardly from their fulcrums, and terminate above the supporting pins N' and N^2 , projecting laterally from the opposite sides of a bracket N^3 which extends from the supporting frame W^3 . The levers M' and M^2 are provided with upwardly projecting cams m' and m^3 which are adapted to be engaged by rollers n' and n^2 , respectively, secured to the opposite ends of a lever N fixed to the shaft D' .
- 30 The opening of the valves prior to the operation of the impulse mechanism insures the air in the service pipes being at atmospheric pressure so that the expansion or contraction of the air in the tubes owing to changes in temperature will in no wise interfere with the proper operation of the system. If no valves were employed and the service tubes were closed to the atmosphere a contraction of the air would impose a load upon the motor in distending the bellows, while on the other hand, the expansion of the air would increase the power necessary to compress the bellows. The opening of each
- 35 valve prior to the expansion of the bellows communicating with the corresponding service pipe also serves to replace any air which may have escaped owing to leakage in the system.
- 40 An oscillatory detent frame P is journaled upon a rod p , the opposite ends of which are mounted in bearings w^3 and w^4 projecting upwardly from the supporting frame. The frame P is provided with an arm P' projecting inwardly and having a lateral bent portion which overlies the levers M' and M^2 . Extending from the frame P at the opposite side of its fulcrum from the arm P' , is a counterbalance weight p' .
- 45 Pivots supported upon the frame P is an oscillatory member R one downwardly extending end of which is pivotally secured to the arm P' , while the other end thereof which is pivoted to the extension of p^2 of the frame P , projects downwardly forming a detent lever r the lower end of which extends into the path of movement of a series of pins s', s^2 , etc., fixed upon the gear wheel S of a time train. Any suitable time train may be employed, such as illustrated in Fig. 1, and as the operation of such mechanism is well known it need not be further described in detail.
- 50 r^3 indicates an adjustable stop, against which the detent lever r normally rests, as shown in Fig. 1.
- 55 The member R is provided with downwardly extending hangers r' and r^2 , which are adapted to alternately support the ends

of the levers M' and M^2 . The positions of the hangers r' and r^2 may be adjusted by means of such screws r^3 supported in a bracket R^3 depended from the member R .
5 The member R is provided with an outwardly extending arm R' which serves as a weight to counterbalance the detent lever r . Extending beneath the extension p^2 of the oscillatory detent frame P is a supporting 10 pin w^7 , upon which the frame normally rests.
A lever O is fulcrumed upon a shaft O^2 , the ends of which are supported in bearings w^5 and w^6 projecting upwardly from the supporting frame. Extending outwardly 15 from the shaft O^2 is a counterbalance weight o^3 secured to the end of the lever O . The opposite end of the lever O from the weight o^3 is provided with a pawl O' , which is adapted to alternately rest upon lugs o' and o^2 projecting from the levers M' and M^2 , thereby supporting the lever O in position 20 to retain the upwardly projecting finger o thereon in the path of the stop arm d^3 which projects from the shaft D^2 . The lever O is provided with a cam o^4 adapted to be alternately engaged by rollers n , n , carried by the lever N at opposite sides of the shaft D' .
Fulcrumed upon the upper end of the supporting frame W' immediately above the lever E is a tube G either straight or having enlarged ends g , and containing a rolling weight such as mercury, lead or any heavy substance. An arm G' is rigidly secured to 30 and depends from the lever G at a point adjacent its fulcrum. The lower end of the arm G extends into the path of movement of pins g' projecting inwardly from the gear wheel c' . Rigidly secured to the lever G at 35 a point adjacent its fulcrum is a toothed segment g^3 , which meshes with a toothed segment g^4 pivotally supported between the frame W' and a strap V' . Rigidly secured to and depending from the segment g^4 is an 40 arm G^2 , the lower end of which extends into the path of movement of pins g^2 projecting from the gear wheel c' at the opposite side thereof from the pins g' . The pins g^2 are located intermediate of the pins g' as clearly 45 shown in Fig. 9. The lever G is adapted to rest upon either a support e' in the form of a roller carried by the lever E or upon a bracket e^2 also carried by the lever E at the opposite side of its fulcrum from the roller e' .
50 The operation of my invention is as follows: At predetermined intervals, such for instance, as each minute, one of the pins s' , s^2 , etc., on the gear wheel S of the time train, engages the lower end of the detent lever r and oscillates the same sufficiently to disengage the hanger r' or r^2 from beneath the inner end of the lever M' or M^2 . When the parts of the mechanism are in the positions indicated in Figs. 1 and 2, the valve L' is closed by reason of its actuating lever M' be- 55 ing supported by the hanger r' . The system of clocks in communication with the service pipe H' have been actuated by an impulse of air produced by the compression of the bellows F' while the system of clocks in communication with the service pipe H^2 have been actuated by the return of the air to the distended bellows F^2 under normal conditions and also by the escape of air through the valve L^2 , in case of change of temperature. 60 A slight oscillation of the detent lever r through the contact therewith of the pins s' removes the hanger r' from beneath the inner end of the lever M' , thereby opening the valve L' and permitting the air under pressure, to be released from the service pipe H' . The release of pressure from the service pipe H' together with the distension of the bellows F' actuates the air chambers at the various subordinate clocks, so that the hands thereof 65 are moved forward one minute, or any other predetermined distance corresponding to the master clock. The movement of the lever M' from its position upon the hanger r' to its place of rest upon the supporting pin N' , removes the supporting lug o' thereon from beneath the pawl O' on the end of the lever O thereby permitting the latter to fall from the position shown in Fig. 2 to that shown in Fig. 3. The oscillation of the lever O removes the finger o thereon from the path of movement of the arm d^3 on the shaft D^2 , thereby permitting the rotation of such shaft and the consequent operation of the motor. 70 The weights through the supporting cords a rotate the drums a' and a^2 , which in turn rotate the power shafts A' and A^2 . The gear wheels B' and B^2 fixed upon the power shafts rotate the shaft B through their engagement with the pinion b . The rotation of the shaft B rotates therewith the gear wheel C which in turn rotates the gear wheel c and the shaft C' upon which it is fixed. The gear wheel c' rotates with the shaft C' and through the pinion d' which it engages, rotates the shaft D' . The shaft D' rotates the crown gear D thereon, which meshes with the pinion d^2 fixed upon the shaft D^2 , thereby revolving the fly governor D^3 .
75 The rotation of the shaft D' carries the roller n^2 on the lever N into engagement with the cam m^2 on the lever M^2 , thereby oscillating the latter from the position shown in Fig. 3 to that shown in Fig. 4, in which the end thereof is in position to fall upon the hanger r^2 when the roller n^2 passes from beneath the cam m^2 . The oscillation of the lever M^2 through engagement with the arm P' oscillates the frame P and with it the detent member R so that the hanger r^2 is swung into position to receive the end of the lever M^2 . The oscillation of the frame P by the lever M^2 lifts the detent lever r from engagement with the pin s' into position to be engaged by the following 80 85 90 95 100 105 110 115 120 125 130

pin s^2 on the time train gear wheel S. The elevation of the lever M^2 closes the valve L^2 thereby cutting off the communication between the service pipe H^2 and the atmosphere, so that the compression of the bellows F^2 , the operation of which will be subsequently described, will force an air impulse through such service pipe and actuate the air chambers at the various subordinate 10 clocks so that the latter are moved forward the predetermined degree, corresponding to the master clock. The continued rotation of the shaft D' moves one of the rollers n into engagement with the cam o^4 on the lever 15 O so that the latter is oscillated from the position shown in Fig. 4 to that shown in Fig. 5, with the result that the pawl O' is in position to fall upon the lug o^2 on the lever M^2 when the roller n passes from beneath 20 the cam o^4 . The stop finger o on the lever O is consequently elevated from a supporting pin o^5 (see Fig. 1) into such a position that the upper end thereof lies within the path of movement of the arm d^3 so that 25 the motor will be again stopped upon the arm d^3 engaging the upper end of the finger o . The motor then continues out of operation until the movement of the time train oscillates the detent lever r sufficiently to 30 remove the hanger r^2 from beneath the lever M^2 , permitting the latter to fall upon the supporting pin N^2 . The falling of the lever M^2 closes the valve L^2 , permitting the escape 35 of the compressed air to the atmosphere from the service pipe H^2 , thereby in conjunction with the subsequent distention of the bellows F^2 actuating the air chambers in communication therewith and moving the subordinate clocks forward the predetermined degree. The falling of the lever M^2 40 also serves to remove the lug o^2 from beneath the pawl O' , so that the lever O drops, upon the supporting pin o^5 thereby removing the stop finger o from the path of the arm d^3 , permitting the motor to again run. The operation of the motor rotates the lever N , which carries the roller n' into contact 45 with the cam m' , thereby elevating the lever M' , which closes the valve L' and places the service pipe H' in condition to receive the impulse of air generated by the compression of the bellows F' . The lever M' is retained in its elevated position by the hanger r' , which is oscillated below the same 50 through the engagement of such lever with the portion P' of the detent oscillating frame P . The motor continues to run until one of the rollers n engages the cam m^3 on the lever O , thereby swinging the same upwardly and projecting the stop finger o into the path of the arm d^3 , the lever being retained in such position by the pawl O' resting upon the lug o^2 on the lever M' as shown in Fig. 2.

It will be observed that when either of the levers M' or M^2 is supported by the corresponding hanger r' or r^2 , it forces downwardly the yoke on the corresponding valve stem l' or l^2 , thereby seating the valve L' or L^2 so as to close the corresponding branch pipe K' or K^2 from communicating with the atmosphere through the ports k^3 or k^4 . The movable collar l^3 on each valve stem serves through the compression of the spring l to permit the inner end of the corresponding lever to move upwardly even after the corresponding valve has been seated, thereby permitting the inner ends of the levers to be swung upwardly in position to fall upon the hangers and insuring the valves being tightly closed after the levers have moved from the positions such as that of the lever M^2 in Fig. 4, to that of said lever as shown in Fig. 5.

Operation of impulse mechanism.—When the mechanism is in the condition shown in Fig. 1, the release of the motor oscillates the lever E through the link e connecting the same with the crank d on the shaft D' . The oscillating of the lever E compresses the bellows F^2 and distends the bellows F' . The compression of the bellows F^2 forces the air through in the service pipe H^2 , the exhaust valve L^2 leading therefrom having been previously closed as above described, and actuates the subordinate clocks through the medium of their air chambers. It is evident that the power required to compress the bellows gradually increases and that in a construction such as that covered by my prior patent above referred to, the motor must be of sufficient power to exert the requisite force to complete the compression of the bellows. In my present improvement, during the first part of the compression of the bellows when there is no resistance, the otherwise wasted power is utilized to oscillate the tube containing a rolling weight, so that the work of the motor in completing the compression of the bellows is as- sisted by the weight.

The tube is oscillated at a little greater speed than the motion of the bellows lever E so that before the latter has reached a horizontal position, at which the air resistance is rapidly increasing, the oscillating tube is tipped and the weight therein has rolled to the other end thereof and assists the power of the motor to complete the compression of the bellows. For example, if it requires 16 ounces for the final compression of the bellows, 9 ounces will be exerted by the power of the motor and 7 ounces by the weight. At the commencement of the operation of the motor the 9 ounces exerted thereby lift up 7 ounces of weight which acts with the motor during the latter part of its operation. If in actual practice it takes a weight of 100

5 pounds to operate an eight day motor to compress the bellows for a certain number of clocks, the employment of a rolling weight of 45 pounds enables a weight of 55 pounds to operate the system in lieu of a weight of 100 pounds. The employment of a lighter weight permits a motor of lighter construction to be used with less internal friction and with a slight gain in initial force, in addition 10 to permitting the use of a clock case of smaller size.

In Fig. 9 the impulse mechanism is illustrated as in a position resulting from an operation of the motor sufficient to partially 15 compress the bellows F^2 and to bring a pin g' on the gear wheel c' into contact and slightly oscillate the lower end of the arm G' , the upper end of which is rigidly secured to the weight carrying tube G . The further operation 20 of the motor causes the pin g' to move the arm G' a distance to oscillate the lever from the position shown in Fig. 1, to one in which the weight within the tube G is supported upon the bracket e^2 on the lever E . 25 The subsequent operation of the motor is therefore performed by the weight within the tube G and the power of the motor necessary to compress the bellows is correspondingly reduced. When the bellows F^2 has been 30 compressed the initial succeeding operation of the mechanism opens the valve L^2 thereby releasing the air in the service pipe H^2 , while the valve L' leading from the service pipe H' is closed. The operation of the motor 35 through the shaft D' , crank d and link e oscillates the lever E in a direction to compress the bellows F' . An operation of the motor sufficient to partially compress the bellows F' , as shown in Fig. 10, brings one of the pins 40 g^2 on the gear wheel c' into contact with the arm G^2 and oscillates the latter, which through the meshed segments g^4 and g^3 oscillates the tube G from the position shown in Fig. 10 to that shown in Fig. 1, thereby shifting 45 the rolling weight into position to aid the motor in completing the compression of the bellows F' .

The bellows F' and F^2 may either or both be adjusted towards or away from the fulcrum of the lever E , thereby varying the degree of the distention and compression of the bellows according to the number of supplemental clocks in communication with the respective service pipes H' and H^2 . Such adjustment of the bellows may be readily accomplished by removing the pins f and sliding the blocks h' and h^2 between the plate H and frame W . The clamp screws engaging the block and extending through slots in the plate H serve as convenient means for securing the blocks in any desired position. After the blocks have been adjusted the pins f are inserted through the holes in the upper ends of the rods f' and f^2 and through corresponding holes in the ends of the lever E .

It will be observed that the valves L' and L^2 seat with the pressure so that the pressure assists in securely retaining the valves in close contact with their seats when there is pressure in the service pipes.

70

By employing a direct detent in place of the usual warning detent, a minimum load is imposed upon the time train as it is only necessary that the detent lever should be slightly oscillated in order to remove the hanger r' or r^2 from beneath the end of the lever M' or M^2 . The work of alternately lifting the levers M' and M^2 as well as lifting the lever O is imposed upon the motor which also through the alternate engagement of the levers M' and M^2 with the portion P' of the detent swinging frame, lifts the detent lever from engagement with one pin on the time train and locates the same in position to be engaged by the succeeding pin.

85

From the foregoing description it will be observed that I have invented an improved pneumatic clock system, in which the motive power required to run a given number of clocks is reduced approximately one half by utilizing the waste power at the beginning of the operation of the motor through the medium of the rolling weight to assist the motor during the latter part of its operation when the greatest power is required in which a minimum load is placed upon the time train in tripping the motor; and in which the pressure in the service pipes assists the seating of the valves.

90

Having now fully described my invention, what I claim as new and desire to secure by Letters Patent is:

100

1. In a pneumatic clock system, the combination with a service pipe, of impulse mechanism communicating with said pipe for varying the air pressure therein operatively connected to said mechanism, a lever for actuating said mechanism, a motor connected to said lever for oscillating the same so as to cause the said mechanism to be actuated 105 to vary the pressure in said pipe, a shifting weight, means actuated by said motor for shifting the center of gravity of said weight independently of the lever and prior to the oscillation of said lever to its intermediate 110 position, and means for applying said weight when shifted to assist the motor in oscillating said lever.

115

2. In a pneumatic clock system, the combination with two service pipes, of impulse mechanism communicating with each service pipe for varying the air pressure therein, a lever fulcrumed intermediate of its ends and connected to each of said mechanisms, a motor connected to said lever for oscillating 120 the same and thereby actuating said mechanisms to alternately vary the pressure in the service pipes, a shifting weight, means for shifting the center of gravity of said weight 125 by the motor prior to the oscillation of said 130

lever to its intermediate position, and means of applying said weight when shifted to assist the motor in oscillating said lever.

3. In a pneumatic clock system, the combination with a service pipe, of impulse mechanism for varying the air pressure in said pipe, a motor for actuating said mechanism, a shifting weight connected to said motor independently of said mechanism so as to be lifted during the first part of the work of the motor in actuating said mechanism and assisting said motor in effecting more than the last half of the operation of said mechanism.

15 4. In a pneumatic clock system, the combination with two service pipes, of impulse mechanism for alternately varying the air pressure in said pipes, a motor for actuating said mechanism, and auxiliary means for utilizing the waste power during less than the first half of the work of the motor to assist the motor during more than the last half of its work.

25 5. In a pneumatic clock system, the combination with two service pipes, of a compressible chamber communicating with each service pipe, a motor for alternately compressing and expanding said chambers, a weight lifted by said motor during less than

30 the first half of its work to assist the motor during more than the last half of its work.

6. In a pneumatic clock system, the combination with two service pipes, of impulse mechanism communicating with each service pipe for varying the air pressure therein, a lever fulcrumed intermediate of its ends and connected to each of said impulse mechanisms, a motor connected to said lever for oscillating the same and thereby actuating said mechanisms to alternately vary the pressure in the service pipes, and means operated by said motor during the initial oscillation of said lever for assisting in more than the last half of the oscillation of said lever.

45 7. In a pneumatic clock system, the combination with a service pipe, of impulse mechanism for varying the air pressure in said pipe, a motor for actuating said mechanism, an oscillatory tube, a rolling weight within said tube, connections between said motor and said tube for causing said tube to be oscillated during the first part of the work of the motor and independently of said mechanism, and means for applying said weight to assist the motor in effecting more than the last half of the actuation of said motor.

8. In a pneumatic clock system, the combination with two service pipes, of impulse mechanism communicating with each service pipe for varying the air pressure therein, a lever fulcrumed intermediate of its ends and connected to each of said mechanisms, a

65 motor connected to said lever for oscillating

the same and thereby actuating said mechanisms to alternately vary the pressure in the service pipes, a shifting weight, means for shifting said weight by the motor at a greater speed than the oscillation of said lever, during less than half of the angular movement of the lever and means for thereafter shifting said weight at the same speed as the lever so as to assist the motor in oscillating the lever. 75

9. In a pneumatic clock system, the combination with two service pipes, of impulse mechanism communicating with each service pipe for varying the air pressure therein, a lever fulcrumed intermediate of its ends and connected to each of said mechanisms, a motor connected to said lever for oscillating the same and thereby actuating said mechanisms to alternately vary the pressure in the service pipes, an oscillatory tube, a rolling weight within said tube, means for oscillating said tube by the motor at a greater speed than the oscillation of said lever, and means for applying said weight to assist the motor in oscillating said lever. 90

10. In a pneumatic clock system, the combination with two service pipes, of impulse mechanism communicating with each service pipe for varying the air pressure therein, a lever fulcrumed intermediate of its ends and connected to each of said impulse mechanisms, a motor connected to said lever for oscillating the same and thereby actuating said mechanisms to alternately vary the pressure in the service pipes, an oscillatory 100 weight fulcrumed in the same vertical plane as the fulcrum of said lever, means for alternately supporting said weight upon said lever at either side of its fulcrum, and means for oscillating said weight by the motor at 105 a greater speed than the oscillation of said lever. 95

11. In a pneumatic clock system, the combination with two service pipes, of impulse mechanism communicating with each service pipe for varying the air pressure therein, a lever fulcrumed intermediate of its ends and connected to each of said impulse mechanisms, a motor connected to said lever for oscillating the same and thereby actuating 110 said mechanisms to alternately vary the pressure in the service pipes, an oscillatory tube fulcrumed in the same vertical plane as the fulcrum of said lever, a rolling weight within 115 said tube, means for supporting said tube upon said lever alternately at either side of its fulcrum, and means for oscillating said tube by the motor at a greater speed than 120 the oscillation of said lever. 120

12. In a pneumatic clock system, the combination with a service pipe, of a compressible chamber communicating with said pipe, a lever adjustably connected to said chamber, a supporting frame upon which said chamber is mounted, means in sliding en- 130

gagement with said frame for adjusting said chamber towards and away from the fulcrum of said lever, and a motor for oscillating said lever.

5 13. In a pneumatic clock system, the combination with two service pipes, of a compressible chamber communicating with each of said pipes, a lever fulcrumed intermediate and adjustably connected to said chambers, 10 a supporting frame upon which said chambers are mounted, means in sliding engagement with said frame for adjusting said chambers towards and away from the fulcrum of said lever, and a motor for oscillating 15 said lever.

14. In a pneumatic clock system, the combination with a service pipe, of a compressible chamber communicating with said pipe, an outwardly seating valve controlling a port 20 leading to the atmosphere from said pipe, a motor for compressing and expanding said chamber, and means operated by said motor for seating said valve prior to compressing said chamber and for unseating said valve 25 prior to expanding said chamber.

15. In a pneumatic clock system, the combination with a service pipe, of a compressible chamber communicating with said pipe, a motor for compressing and expanding said 30 chamber, a valve for controlling a port leading from said pipe to the atmosphere, a lever operatively connected to said valve for seating and unseating the same, and means actuated by said motor for oscillating said 35 lever to close said valve prior to compressing said chamber and for opening said valve prior to expanding said chamber.

16. In a pneumatic clock system, the combination with a service pipe, of a compressible chamber communicating with said pipe, a motor for compressing and expanding said chamber, a valve for controlling a port leading from said pipe to the atmosphere, a valve stem connected to said valve, a lever for 45 seating and unseating said valve, a spring interposed between said lever and valve stem for permitting a movement of the lever relative to the valve stem after the valve has closed, and means operated by the motor 50 for oscillating said lever to close said valve.

17. In a pneumatic clock system, the combination with a service pipe, of a compressible chamber communicating with said pipe, a motor for compressing and expanding said 55 chamber, a valve for controlling a port leading from said pipe to the atmosphere, a valve stem connected to said valve, a lever for seating and unseating said valve, a spring interposed between said lever and valve 60 stem for permitting a movement of the lever relative to the valve stem after the valve has closed, means operated by the motor for oscillating said lever to close said valve, and means operated by a time train for oscillating 65 said lever to open said valve.

18. In a pneumatic clock system, the combination with a service pipe, of a compressible chamber communicating with said pipe, a motor for compressing and expanding said chamber, a valve controlling a port leading 70 from said pipe to the atmosphere, a lever operatively connected to said valve for seating and unseating the same, means actuated by said motor for oscillating said lever to close the valve, an oscillatory frame for supporting said lever in position to close said valve, and a time train for oscillating said frame thereby releasing said lever and opening the valve. 75

19. In a pneumatic clock system, the combination with a service pipe, of a compressible chamber communicating with said pipe, a motor for compressing and expanding said chamber, a valve for controlling a port leading 80 from said pipe to the atmosphere, a lever operatively connected to said valve for seating and unseating the same, means actuated by said motor for oscillating said lever to close said valve, a stop for controlling the operation of said motor, means for supporting 85 said stop upon said lever in position to interrupt the operation of the motor when said valve is closed and to remove said stop from engagement with said motor when the valve is open. 90

20. In a pneumatic clock system, the combination with a service pipe, of a compressible chamber communicating with said pipe, a motor for compressing and expanding said chamber, a valve for controlling a port leading 100 from said pipe to the atmosphere, a lever operatively connected to said valve for seating and unseating the same, means actuated by the motor for oscillating said lever to close said valve, means operated by a time 105 train for oscillating said lever to open said valve, a stop for controlling the operation of said motor, means for supporting said stop upon said lever in position to interrupt the operation of said motor, and means actuated 110 by the motor for lifting said stop into position to be supported upon said lever.

21. In a pneumatic clock system, the combination with a service pipe, of a compressible chamber communicating with said pipe, a motor for compressing and expanding said chamber, a stop for interrupting the operation of said motor, a time train, a detent actuated by the time train for removing said 115 stop from engagement with the motor, and means actuated by the motor for locating said stop in position to interrupt the operation of the motor. 120

22. In a pneumatic clock system, the combination with a service pipe, of a compressible chamber communicating with said pipe, a motor for compressing and expanding said chamber, a stop for interrupting the operation of said motor, a time train, a detent actuated by the time train for removing said 125 130

stop from engagement with the motor, means actuated by the motor for locating said stop in position to interrupt the operation of the motor, an oscillatory frame upon 5 which said detent is pivoted, and means actuated by the motor for oscillating said frame and thereby locating said detent in operative relation to the time train.

23. In a pneumatic clock system, the combination with a service pipe, of impulse mechanism communicating with said pipe, a motor for actuating said impulse mechanism, a valve for controlling a port leading from said pipe to the atmosphere, a lever 10 operatively connected to said valve for seating and unseating the same, means actuated by the motor for oscillating said lever to close said valve, means operated by a time train for oscillating said lever to open said 15 valve, a stop controlling the operation of said motor, a second lever to which said stop is rigidly secured, a pawl pivoted to said second lever adapted to rest upon said first lever and support said stop in position to interrupt 20 the operation of said motor, and means actuated by the motor for lifting said second lever in position for the pawl to rest upon said first lever.

24. In a pneumatic clock system, the combination with a service pipe, of impulse mechanism communicating with said pipe, a motor for actuating said mechanism, a valve controlling a port leading from said pipe to the atmosphere, a lever operatively 30 connected to said valve for seating and unseating the same, means actuated by said motor for oscillating said lever to close said valve, an oscillatory detent frame for supporting said lever in position to close said 35 valve, a detent lever extending from said frame, a time train, pins carried by said time train to successively engage said detent lever thereby oscillating said frame and releasing said lever to open the valve.

45 25. In a pneumatic clock system, the combination with a service pipe, of impulse mechanism communicating with said pipe, a motor for actuating said mechanism to vary the pressure in said pipe, a valve controlling 50 a port leading from said pipe to the atmosphere, a lever operatively connected to said valve for seating and unseating the same, means actuated by the motor for oscillating said lever into position to close said 55 valve, oscillatory means for supporting said lever in position to close the valve, a time train, and means actuated by the time train for swinging said oscillatory means out of engagement with said lever to permit the 60 latter to fall and open the valve.

26. In a pneumatic clock system, the combination with two service pipes, of impulse mechanism communicating with each of said pipes, a motor for actuating said impulse 65 mechanism to alternately vary the pressure

in said pipes, valves for controlling ports leading to the atmosphere from said pipes, levers operatively connected to said valves for seating and unseating the same, means actuated by the motor for alternately oscillating 70 said levers into position to close said valves, oscillatory means for alternately supporting said levers in position to close the valves, a time train, and means actuated by the time train for swinging said oscillatory 75 means alternately from engagement with said levers to permit them to fall and open the valves.

27. In a pneumatic clock system, the combination with a service pipe, of impulse mechanism communicating with said pipe, a motor for actuating said impulse mechanism, a valve for controlling a port leading from said pipe to the atmosphere, a lever operatively connected to said valve to open and close the 80 same, means actuated by the motor for lifting said lever in position to close said valve, an oscillatory frame for supporting said lever in position to close said valve, a detent lever connected to said oscillatory means, a time 85 train, pins carried by said time train adapted to successively engage and oscillate said detent lever, and means actuated by said motor for locating said detent lever in position to be engaged by the successive pin. 90

28. In a pneumatic clock system, the combination with two service pipes, of impulse mechanism communicating with each pipe, a motor for actuating said mechanism to alternately vary the pressure in said pipes, valves 100 for controlling ports leading from said pipes to the atmosphere, levers operatively connected to said valves for opening and closing the same, means actuated by the motor for alternately lifting said levers into position to 105 close said valves, an oscillatory frame for alternately supporting said levers in position to close said valves, a detent lever connected to said frame, a time train, pins carried by said time train adapted to successively engage and oscillate said 110 detent lever, and means actuated by said motor for locating said detent lever in position to be engaged by the successive pins.

29. In a pneumatic clock system, the combination with two service pipes, of impulse mechanism for alternately varying the pressure in said pipes, a motor for actuating said mechanism, and auxiliary means for utilizing the waste power during a small 115 initial portion of the work of the motor when effecting a variation of the pressure in either of said pipes to assist the motor in the performance of the remainder of said work. 120

30. In a pneumatic clock system, the combination with two service pipes, of a compressible chamber communicating with each pipe, a motor for alternately compressing and expanding said chamber, a weight lifted by said motor during a small initial portion 125 130

bers, and means for thereafter causing the weight to assist the motor in the performance of the remainder of said work.

- 5 31. In a pneumatic clock system, the combination with two service pipes, of a compressible chamber communicating with each service pipe, a lever fulcrumed intermediate its ends and connected to each of said chambers, a motor connected to said lever for oscillating the same so as to alternately compress said chambers, a shifting weight, means for shifting said weight by the motor at a greater speed than the oscillation of said lever during a small initial portion of the work by the motor in compressing either of said chambers, and means for thereafter applying said weight to assist the motor in the performance of the remainder of said work.

10 32. In a pneumatic clock system, the combination with two service pipes, of a device associated with each pipe for producing an impulse therein, a motor connected to said device for producing a working stroke in either simultaneously with a return stroke in

15 thereafter to give up energy to the motor 30 during the remainder of each of said working strokes.

20 33. In a pneumatic clock system, the combination with two service pipes, of a compressor connected with each of said pipes, a 35 motor connected to said compressor so as to produce a working stroke in either simultaneously with a return stroke in the other, and auxiliary means actuated by said motor during less than the first half of each of said 40 working strokes to store up energy for assisting the motor during the remaining portions of the said working strokes.

25 In testimony whereof, I sign this specification in the presence of two witnesses.

AUGUSTUS L. HAHL.

Witnesses:

GEO. L. WILKINSON,
C. A. MULLEN.

thereby during less than half of each of said working strokes to store up energy and thereafter to give up energy to the motor 30 during the remainder of each of said working strokes.

33. In a pneumatic clock system, the combination with two service pipes, of a compressor connected with each of said pipes, a 35 motor connected to said compressor so as to produce a working stroke in either simultaneously with a return stroke in the other, and auxiliary means actuated by said motor during less than the first half of each of said 40 working strokes to store up energy for assisting the motor during the remaining portions of the said working strokes.

In testimony whereof, I sign this specification in the presence of two witnesses.

AUGUSTUS L. HAHL.
